UNITED STATES PATENT OFFICE.

OTTO R. BARNETT, OF GLENCOE, ILLINOIS, ASSIGNOR TO P & M COMPANY, OF CHICAGO, ILLINOIS, A CORPORATION OF ILLINOIS.

RAIL-ANCHOR.

1,392,288.

Specification of Letters Patent.

Patented Oct. 4, 1921.

Application filed June 3, 1919. Serial No. 301,428.

To all whom it may concern:

Be it known that I, OTTO R. BARNETT, a citizen of the United States, residing at Glencoe, in the county of Cook and State 5 of Illinois, have invented certain new and useful Improvements in Rail-Anchors, of which the following is a specification.

My invention relates to improvements in that type of devices for preventing the creeping 10 of railway rails, which comprises a yoke provided at opposite ends with jaws for engaging the rail base, and a key or wedge adapted to clamp the jaws of the yoke into gripping engagement with the rail, either 15 the yoke or the wedge being provided with a tie abutting member.

The object of my invention is to provide a device of this character which will be of highest efficiency, simple of design, easy 20 of application and securely attached to the rail at all times regardless of whether or not the tie abutment is in engagement with the tie.

A further object of my invention is to provide 25 a novel wedge for anti-creepers provided with a corrugated surface adapted to bite into the base of the rail and securely hold it against movement in the yoke regardless of the particular form of yoke employed. These and such other objects as 30 may hereinafter appear are attained by my device, certain preferred forms of which are disclosed in the accompanying drawings in which:

Figure 1 is a plan view of a device embodying the principles of my invention as applied to a rail.

Fig. 2 is an end elevational view of the device shown in Fig. 1.

Figs. 3 and 4 are sectional views, respectively, taken on lines 3—3 and 4—4 of Fig. 1.

Fig. 5 is a sectional view taken on the line 5—5 of Fig. 4.

Fig. 6 is a perspective view of the wedge 45 shown in the preceding figures.

Fig. 7 is a cross-sectional view taken on line 7—7 of Fig. 8 showing a modified form of wedge.

Fig. 8 is an end elevational view of the 50 yoke and the modified form of wedge as applied to the base of a rail.

Fig. 9 is a perspective view of the modified form of wedge.

Fig. 10 is a detail view showing the serrated end of the wedge in locking engagement with the edge of the yoke, and

Fig. 11 is a detail view of the end of a sheet metal yoke adapted to engage the serrated end of the wedge.

Like characters of reference designate like 60 parts in the several views.

Referring first to Figs. 1 to 6 inclusive, 12 indicates a railway rail and 13 a tie or other abutment which may be engaged by the depending tie abutment member 14 shown in these views as an integral part of the yoke 15. The yoke is preferably formed with integral jaws 16 and 17, the jaws being slightly bendable or resilient. The jaws are preferably spaced far enough apart and provided with sufficiently deep undercuts to permit the yoke to be slipped over and seated on the base of the rail. The ends of the jaws may be smooth but I prefer to form them with teeth extending transversely with 75 respect to the rail, as shown more clearly in Fig. 3, so as to obtain better gripping action. The jaws 16 and 17 are each formed with the respective perforations 18 and 19 adapted to receive a tapered key or wedge 80 20. The wedge 20 is adapted to be driven through the jaws of the yoke and is interposed between the body of the yoke and the base of the rail. The wedge is provided with a plurality of sharp ridges or corruga-

tions 21 which extend longitudinally of the wedge and which are adapted to bite into the base of the rail when the wedge is driven home. Preferably the corrugations are formed near the middle of the top surface 90 of the wedge so that the central portion of the base of the rail will be gripped when the wedge is driven home. The wedge may be secured in the yoke by up-setting or bending the small end up or down around the edge of the yoke, or by any other suitable means, such as a cotter pin, or the lock-nut 22 threaded on the end of the wedge so that any looseness may be taken up by adjusting the nut 22.

In Figs. 7 to 9 inclusive, I have shown the principles of my invention embod-

ied in a device in which the tie abutting member is formed on the wedge instead of the yoke. The yoke may be of the same type as that shown in my 5 Patent No. 1,248,790 issued December 4, 1917. The wedge 20^a may be held in place in the yoke by providing a plurality of transversely extending teeth 23 formed on the bottom of the wedge which are adapted 10 to engage the edge of the yoke. In this form the wedge is somewhat longer than the yoke, one end thereof being provided with a depending apron 24 which is adapted to abut against the tie.

15 Obviously, however, the toothed interlocking structure between wedge and yoke may be used with the tie abutment on any convenient part of the structure.

When the serrated end is used on the 20 wedge it may interlock with the yoke by snapping over the straight edge of the yoke as shown in Fig. 7 in which the serrated end of the sufficiently resilient wedge has normally a slight downward bend; or the yoke 25 may have a slightly raised edge as at 25 in Fig. 10 over which the serrated edge of the wedge is forced to locking position.

When a sheet metal yoke is used as in my Patent 1,248,790, the end of the resilient 30 yoke may be normally formed with a slightly raised edge 26 to engage the serrated end of the wedge as in Fig. 11, in which event it is not necessary that the wedge be resilient.

35 From the drawings and the foregoing description it will be obvious that the wedge may be applied to yokes of various descriptions. The corrugations formed on the wedge, extending as they do transversely 40 of the rail, bite into the base thereof and effectively prevent loosening of the wedge by any longitudinal movement of the rail.

It is obvious that various departures may be made from the exact structure shown 45 without departing from the spirit of my invention which contemplates such changes in form.

It will be understood that I do not wish to be restricted to the specific form of wedge 50 member shown in the drawings in which the wedge member is given a continuous even taper from end to end, the important feature being that it has a wedging engagement with respect to the jaws 16 and 17 and that the corrugations 21 are forced into 55 proper contact with the rail as the wedge member is forced into position.

I claim:

1. An anti-creeper comprising a yoke 60 adapted to extend transversely under a rail base, jaws at opposite ends of the yoke and in operative relation thereto, provided with means for biting transversely of the rail into the upper surface of the base flange 65 of said rail, a wedge adapted to be driven

between the yoke and the rail base to cause said jaws to tightly grip the rail base, means on said wedge for biting transversely of the rail into the bottom of the rail base when the wedge is driven to gripping position, 70 and means on the structure to engage a stationary part of the road bed.

2. An anti-creeper comprising a yoke adapted to extend transversely under a rail base, jaws at opposite ends of the yoke and in operative relation thereto, provided with means for biting transversely of the rail into the upper surface of the base flange of said rail, a wedge adapted to be driven between the yoke and the rail base to cause 75 said jaws to tightly grip the rail base, means on said wedge for biting transversely of the rail into the bottom of the rail base when the wedge is driven to gripping position, means on the structure to engage a stationary part of the road bed and means for automatically locking the wedge in gripping position.

3. An anti-creeper comprising a yoke member adapted to extend underneath the 90 rail and provided at each end with a rail gripping jaw, a wedge member adapted to be interposed transversely of the rail between the base of the rail and the body of said yoke, said wedge having corrugations extending longitudinally of the wedge adapted 95 to engage the base of the rail when the wedge is driven home, and a tie abutting element formed on one of said members.

4. An anti-creeper comprising a yoke 100 member adapted to extend underneath the rail and provided at each end with a rail gripping jaw, a wedge member adapted to be interposed transversely of the rail between the base of the rail and the body of 105 said yoke, said wedge having sharp ridges extending longitudinally of the wedge and adapted to bite into the base of the rail when the wedge is driven home, and a tie abutting element formed on one of said members.

5. An anti-creeper comprising a yoke member adapted to extend underneath the rail and provided at each end with a rail gripping jaw, a wedge member adapted to be interposed transversely of the rail between the base of the rail and the body of 115 said yoke, said wedge having a corrugated surface adapted to bite transversely of the rail into the base of the rail when the wedge is driven home so as to prevent displacement of the yoke longitudinally of the rail in either forward or rearward direction, means to hold the wedge from slipping backwardly in the yoke and a tie abutting element formed on one of said members.

6. An anti-creeper comprising a yoke adapted to extend underneath the rail, provided at each end with a rail gripping jaw and having a tie abutting member, and a wedge adapted to be placed transversely of 120 125 130

the rail underneath the base of the rail in said yoke, said wedge having sharp ridges extending longitudinally of the wedge and adapted to bite into the base of the rail 5 when the wedge is driven home.

7. An anti-creeper comprising a yoke adapted to extend underneath the rail, provided at each end with a rail gripping jaw and having a tie abutting member, and a 10 wedge adapted to be interposed transversely of the rail between the base of the rail and the body of said yoke, said wedge extending through the jaws of the yoke.

8. An anti-creeper comprising a yoke 15 adapted to extend underneath the rail, provided at each end with a rail gripping jaw and having a depending tie abutting member, a wedge adapted to be interposed transversely of the rail between the base of the 20 rail and the body of said yoke, said wedge extending through the arms of said yoke and having sharp ridges adapted to bite into the base of the rail when the wedge is driven home and means to prevent the 25 wedge from slipping backwardly in the yoke.

9. An anti-creeper comprising a yoke, adapted to extend underneath the rail, provided at each end with a rail gripping jaw 30 and having a depending tie abutting member, a wedge adapted to be interposed transversely of the rail between the base of the rail and the body of said yoke, said wedge having a corrugated surface adapted to 35 engage the base of the rail when the wedge is driven home, said wedge having teeth on the small end thereof and arranged to engage one end of the yoke to prevent the

wedge from slipping backwardly in the yoke. 40

10. An anti-creeper comprising a yoke adapted to extend underneath the rail, provided at each end with a rail gripping jaw and having a depending tie abutting member, a wedge adapted to be interposed transversely of the rail between the base of the rail and the body of said yoke, said wedge having a corrugated surface adapted to engage the base of the rail when the wedge is driven home, said corrugated surface 50 being so formed on the top of the wedge that it will extend transversely under the web of the rail when the wedge is driven home. 45

11. An anti-creeper comprising means 55 provided with jaws for engaging opposite edges of the base flange of a rail and a wedge adapted to be driven into wedging engagement between said jaw means and the rail base; said jaws and wedge members being formed to take a biting hold on the rail base transversely thereof when applied. 60

12. An anti-creeper comprising means 65 provided with jaws for engaging opposite edges of the base flange of a rail, and a wedge adapted to be driven into wedging engagement between said jaw means and the rail base; said jaw and wedge members being formed to take a biting hold on the 70 upper and lower surfaces of the rail base at points within the vertical edges of said rail base when the device is in its operative position.

OTTO R. BARNETT.
